UNITED STATES PATENT OFFICE.

DON CARLOS TRAVIS AND FRANK BLACKMER, OF KENOSHA, WISCONSIN, ASSIGNEES
TO SIMMONS MANUFACTURING COMPANY, OF KENOSHA, WISCONSIN, A CORPORATION
OF WISCONSIN.

FOLDING COUCH.

1,050,873.

Specification of Letters Patent. Patented Jan. 21, 1913.

Application filed September 28, 1911. Serial No. 651,741.

To all whom it may concern:

Be it known that we, DON CARLOS TRAVIS and FRANK BLACKMER, citizens of the United States, residing in the city of Kenosha, county of Kenosha, and State of Wisconsin, have invented certain new and useful Improvements in Folding Couches, of which the following is a specification.

This invention relates to improvements in couches and refers more particularly to a device of that character which when folded may be used as a couch and when open or extended may be employed as a bed.

Among the salient objects of the invention are to provide a construction which when used as a couch has its folded or upper frame spaced away from and supported above the lower frame, to obtain the desired height, the space between the two frames of the couch serving to contain or inclose the top mattress and to provide in a construction of the above character novel means for connecting the respective halves or sections of the metallic mattress; to provide a construction in which the folding legs of the upper frame are self-locking when the device is in open position for use as a bed and which are at the same time released and folded out of the way when the structure is closed for use as a couch; to provide a device which is characterized both as to its frame work and operating parts by its simplicity and economy of construction and which is devoid of complicated or noisy locking members; and in general to provide improvements in the details of construction hereinafter more particularly pointed out.

In the drawings,—Figure 1 is a top plan view of the device shown in folded position for use as a couch. Figs. 2 and 3 are respectively, side and end elevations of the same. Fig. 4 is a transverse vertical sectional view. Fig. 5 is an end elevation of the couch when in extended or open position. Fig. 6 is a top plan view of the construction shown in Fig. 5. Fig. 7 is a detailed view showing one loop for connecting the two sections of the wire mattress.

Describing first the device when used as a

couch, 1 and 2 designate as a whole the lower 50 and upper frame members respectively, to which are secured metallic fabrics 3 and 4 respectively. The lower frame member 1 comprises side rails 5 and 6, and end rails 7 and 8, the frame as a whole being supported by legs 9, all of which preferably take the form of angle irons. The frame is strengthened by means of braces 10 and 11 and is preferably mounted on casters 12. The lower ends of the legs are also connected by 60 tie straps 13. It will be noted that the rear legs 9 project a considerable distance above the plane of the lower frame to form supporting posts 9' for the purpose hereinafter described. 65

Referring now to the upper frame member, it is generally similar in construction having side rails 14 and 15 and end rails 16 and 17. The end rails of the upper member are also formed of angle irons while the side 70 rails are formed from hollow metal rods or pipes. The front side rail 15 is bent downwardly as shown in Fig. 2 in order that it may lie a substantial distance below the mattress when the device is in open position for 75 use as a bed.

The upper frame member is connected to the lower frame in the following manner: to the rear extensions 9' are pivotally connected as shown at 18, one end of a brace 80 link or strap 19, the other end of which is pivotally connected to the front side rail 15 of the upper frame member as shown at 20. To the lower frame is secured by a pivot 21, a supporting link 22 which extends diagonally upwardly and is secured to the upper frame by a pin and slot connection 23. The lower ends of these supporting straps 22 extend below the pivots 21 and engage stops 24. The arrangement is such that when the 90 upper frame member is in folded position the lower ends of these straps 22 strike against the pins 24 and thus support the front end of the upper member in an obvious manner. The pin and slot connection 95 described permits the upper frame member to swing readily into its open or closed position. The rear end of the upper frame rests

upon the extensions 9' of the rear legs and is supported thereby.

As heretofore stated the upper section when it is in its open position is supported as to its front end by means of legs 25 which move to extended position as the device is opened. These legs are pivotally connected intermediate their ends as shown at 26 to the end rails of the upper frame. The upper ends of these legs in turn connect to combined braces and locking links 27 by means of pin and slot connections 28 and 29 respectively. The other ends of these links 27 are pivoted to the end rails of the lower frame as shown at 30. It is understood, of course, that the links and legs above described are provided with suitable off-sets in order that they may swing by each other without binding.

20. When the device is in its open position as shown in Figs. 5 and 6 the legs 25 are locked against movement in either direction by means of the brace members 27, at the same time the arrangement is such that when the upper section is folded into closed position the brace links 27 as they fold back into their normal position retract legs 25 and fold them down below the plane of the upper mattress. In order that the legs 25 may 25 pass below the upper member when in closed position, they are preferably bent slightly rearwardly as shown at 25'. In a similar manner when the upper section is moved into its open position to form the bed, the links 27 swing the legs forwardly into substantially vertical position. The construction above described is such that the upper frame member may be manually swung into either of its positions without the necessity 30 of releasing any locking device and at the same time the legs are both automatically locked and automatically released.

Referring now to the wire mattress, it is 40. preferably formed in two sections, one for the upper frame and one for the lower frame member. The wire mattress may of course be of any suitable form, in the present instance comprising long links 31 and connecting cross links 32. The ends of the 45 mattress are secured to the end rails by coil springs 33, all in a well known manner. The rear edge of the upper half of the mattress is also secured to the side rail 14 by a plurality of coil springs 34. At the rear 50 end of the lower frame is a mattress guard 35 formed by an extension of the fabric itself and similarly connected to the extensions 9' of the rear legs by coil springs 36.

The front end of the couch is also provided 55 with a mattress guard designated 37, which connects the front edges of the mattress sections as shown. This front mattress guard consists of a plurality of wire loops

each formed from a single piece of wire bent into the shape shown in Fig. 7. Each 60 of these loops comprises leg portions 38 and 39 and connecting portion 40; the latter being of substantially the same length as the long links 31 of the mattress. The leg portions 38 and 39 of these loops extend freely 65 through eyes 41 in the lower mattress and are hooked into similar eyes 42 in the upper mattress. These loops 37 are spaced apart as shown; and when the device is used as a couch, they serve as a mattress guard while 70 at the same time permitting the upper half of the wire fabric to be freely depressed. When the upper section is swung into its open position as shown in Fig. 6 these loops serve to connect the adjacent edges of the 75 wire mattress sections, the closed ends of the loops sliding freely beneath the lower half of the wire mattress. The arrangement is such as to form in effect a single continuous mattress.

85 The operation of the device is apparent from the foregoing and therefore need not be described.

The invention is not limited to the details of construction shown except as set forth in 90 the appended claims.

We claim as our invention:

1. In a device of the character described, the combination with a relatively stationary lower frame member, of supporting legs for 95 the same, a movable upper frame member adapted to be extended into a position alongside the lower frame member or folded above and spaced away from the latter, legs for supporting the upper frame member 100 when in its extended position, and means for supporting the upper frame in its folded position comprising posts extending above the rear end of the lower frame member, and links pivotally connected intermediate their 105 ends to the front of the lower frame member and connected at their upper ends to the movable member by a pin and slot connection, and stops for limiting the movement of the said links when the upper member is in 110 its folded position.

2. In a device of the character described, the combination with a lower frame member, of a movable upper frame member adapted to be extended into a position 115 alongside of the lower frame member or folded into a position above and spaced away from said lower frame member, legs for supporting the outer end of the upper frame member when in its extended position, means carried by the rear end of the lower frame member for supporting the outer end of the upper frame when the latter is folded and means for supporting the rear end of the upper frame in its folded position comprising links pivotally connected 120 125

to the lower frame and pivotally connected at their upper ends to the upper frame at points on the latter laterally distant from the pivotal connections of the links with the lower frame, whereby said links are inclined rearwardly when the upper frame is in folded position and stops in the lower frame adapted to engage the lower part of the links when the upper frame is in folded position.

DON CARLOS TRAVIS.
FRANK BLACKMER.
